UNITED STATES PATENT OFFICE

152,151

DESIGN FOR A FIRE GRATE

Fred W. Goodwin, Berkeley, Calif.

Application December 31, 1946, Serial No. 135,857

Term of patent 14 years

(Cl. D81—18)

To all whom it may concern:

Be it known that I, Fred W. Goodwin, a citizen of the United States of America, residing at Berkeley, in the county of Alameda and State of California, have invented a new, original, and ornamental Design for a Fire Grate, of which the following is a specification, reference being had to the accompanying drawing, forming part thereof.

Figure 1 is a perspective view of a fire grate, embodying my new design, and

Figure 2 is an end view thereof.

I claim:

The design for a fire grate, substantially as shown.

FRED W. GOODWIN.
